FOLDING MACHINE

William Jonathan Neidig, Chicago, Ill.

Application December 19, 1931, Serial No. 582,142

36 Claims. (Cl. 270—66)

The invention embodies features more broadly claimed in my pending applications for United States patent, Serial No. 377,255, filed July 10, 1929, and Serial No. 488,087, filed October 11, 1930, now become United States Patent No. 1,838,106 dated December 29, 1931 as will be explained later. It consists in improved means for folding separate sheets of material such as paper, including the positioning, adjusting and discharging devices connected therewith. It makes use of means for advancing a sheet, whether from an earlier folding or still unfolded, into the control of devices that stop it in folding position, give it the desired fold or folds, and then discharge it from their control.

One of the objects of my invention is to simplify the adjustments needed in changing from one fold to another, so that machine folding can be employed economically upon small runs of sheets, using operators relatively unskilled. Another object is to enable the operator to make his adjustments in the open, within convenient reach of his hand. Another object is to enable him to make any adjustment with safety while the machine is running. Another object is to enable him to use wider paper for a given width of machine as compared with certain other embodiments of the invention. Another object is to supply him with indicating means effective at the feed-board to indicate where a given later fold will fall, without requiring him to enter and spoil a sheet to find out. Another object is to supply means for preventing displacement of the sheet by the folding operation. Another object is to supply means effective to remove a folded sheet from stationary folding devices with a minimum distortion of the fold. Another object is to supply means for giving any required degree of softness to a longitudinally extending fold. Another object is to supply a mechanism that can be manufactured flexibly, whether in a simple form for simple uses or embodying features desirable in more complex uses. Other objects are described in the annexed claims.

I attain my several objects by the mechanism illustrated in the accompanying drawings, in which—

Figure 1 represents a side elevation, partly in section, of one of the embodiments of my invention, the structure being broken away in places to show more clearly the structure behind. Fig. 1a illustrates a detail of the same. Fig. 2 is a plan view of the mechanism shown in Fig. 1, the structure likewise being broken away in places. Fig. 3 is a plan view of another embodiment of the invention, using certain portions of the structure shown in Figs. 1 and 2, some of which it is sufficient to describe without repeating it in the drawing. Fig. 4 comprises a view of Fig. 1 from the left, on the line F4—F4, partly in section, and

with certain parts omitted or broken away. Fig. 5 comprises a view in vertical section of Fig. 1, on the line F5—F5, with certain parts omitted.

In both of said embodiments I make use of folding devices for producing a preliminary transverse fold when such is required and of folding devices for producing at will a longitudinal fold or folds. For producing the transverse fold I prefer to employ devices of the usual knife-blade and pressure-roll type, well known in the art, but any approved folding mechanism may be employed, and in some uses no transverse folding devices may be needed. In these embodiments I employ the transverse folding devices in their additional functions as sheet-entering and sheet-advancing means, as is commonly done in commercial practice, without limiting myself to their use.

The construction referred to is described as follows: The usual folding knife is indicated at 1, and the usual pressure rolls at 2 and 3, spring-pressed together by usual springs not necessary to be shown, into the bite of which the downwardly-actuated knife carries the sheet, said rolls having their axles 4 and 5 suitably journaled in or upon side frames 6. Said rolls are rotated from drive shaft 7, journaled at either end in side frames 6, through sprocket wheel 8 attached thereon, sprocket wheel 9 attached on axle 4, chain 10 connecting said sprocket wheels, toothed wheel 11 attached on axle 4, and toothed wheel 12 attached on axle 5, said latter wheels meshing. The knife is operated from toothed wheel 13 attached upon shaft 14, which is journaled at either end in side frames 6, through cam 15 on said wheel and the following connecting devices: Arms 16, which carry the knife, are attached upon shaft 17, journaled at either end in side frames 6 and having a coiled spring attached to act rotatably thereon, indicated at 18. One of said arms bears an outstanding pin 19, on which is journaled rod 20, said rod being journaled at the other end upon pin 21, carried by arm 22, which in turn is journaled at one end upon pin 23 on one of side frames 6. Cam roller 24 is also journaled upon pin 21. Toothed wheel 13 is driven by toothed wheel 25 meshing therewith, attached on drive shaft 7.

The mechanism described is substantially that in common use for making a fold in a sheet, and for advancing, or assisting to advance, the sheet into the control of other operative devices. My invention is in no way dependent upon its use. It will be understood moreover that the advancing and positioning of a sheet for the preliminary folding operation is commonly performed in practice by feeder devices or the like, such devices in effect operating in combination with the first stage folding devices, and that my invention is in no way prevented from making use of such devices when employed in the first folding stage.

The embodiments of the invention illustrated in the drawings preferably make use of the mechanism just described for the purposes referred to. They also make use of sheet-positioning means, 5 of tongue-like or finger-like forming members over which the sheet may be folded, of clamping devices for preventing the displacement of the sheet by the folding operation, of reciprocating devices effective to fold the sheet over the forming members, of devices preventing displacement of the fold, of time-saving adjusting devices, of retractable discharging and sealing devices, and of indicating devices effective at the feed-board to indicate in advance where a fold will fall upon 10 the sheet.

I will first describe the embodiment shown in Figs. 1 and 2, beginning with the supporting structure. It will be understood that similar symbols of reference are employed throughout the drawings 15 20 described herein, to indicate similar parts.

Attached at either end upon side frames 5 is the transversely extending rod or beam 26, upon which sub-frames 27 and 27^r are supported slidably. A second support for said sub-frames is 25 supplied by shaft 14, already described. The sub-frames carry certain of the separable devices hereinafter described. I prefer in this embodiment to provide lateral movement for both sub-frames, although in some uses only one will have 30 an adjustable lateral position, and in some uses neither will have. The moving laterally of either with respect to the other of course renders them separable. The lateral position of said sub-frames upon supports 26 and 14 is controlled by three 35 pairs of threaded shafts indicated at 28 and 28^r, the three shafts 28 being journaled at one end in the left-hand side frame 6, and the three shafts 28^r being journaled at one end in the right-hand side frame 6. Said pairs are connected end 40 to end by means of a dovetail construction 29 and pins 30, so that each pair will constitute in effect a single shaft having on it right-hand and left-hand threads. The threaded portions of shafts 28 engage with the threads of tapped holes in sub-frame 27, and the threaded portions of shafts 28^r engage with the threads of tapped holes in sub-frame 27^r. Shafts 28 and 28^r have attached 45 upon them respectively sprocket wheels 31 and 31^r. A fourth pair of threaded shafts, indicated 50 at 32 and 32^r, likewise connected end to end by a pin 30, are similarly journaled in frames 6. The threaded portions of these shafts engage respectively with the threads in tapped holes in blocks 33 and 33^r, supported slidably upon rods or rails 55 34 and 35, attached at either end upon side frames 6. The purpose of employing both rails is to support said blocks against pressure tending to turn them upon either. Shafts 32 and 32^r have attached upon them respectively sprocket wheels 36 and 36^r and handles 37 and 37^r. It will be understood 60 that sprocket wheels 31 and 36, and sprocket wheels 31^r and 36^r, have the same number of teeth; and that the pitch and direction of threads upon shafts 28 and 32, and upon shafts 28^r and 32^r, will be the same. In this construction the 65 rotation of shafts 28 and 32, and of shafts 28^r and 32^r, is synchronized by chains 38 and 38^r connecting their respective sprocket wheels. Since sub-frame 27 is supported laterally at three 70 points, that is to say tripod-wise, by its three threaded shafts, and the rotation of these shafts is synchronized, the rotation of any one of them will rotate all, and in the resultant change of lateral position its operative plane will remain 75 constant. The same is true of sub-frame 27^r.

Furthermore, since the rotation respectively of the fourth pair of threaded shafts is synchronized with that of these three, sliding block 33 will participate in all lateral movements of sub-frame 27, and sliding block 33^r in all lateral movements of sub-frame 27^r, and the lateral relationship respectively of the same will remain constant.

The forming members over which the sheet is folded in this embodiment are indicated at 39 and 39^r. They are constructed tongue-like or finger-like, that is to say, supported in cantilever manner from one end. In this case they are supported respectively by sliding blocks 33 and 33^r, upon which they are attached. I prefer to construct them having a symmetrical contour in lateral cross-section, in this case with a centrally projecting corner adjacent to the folding line, or as in Fig. 3 presenting a symmetrically rounded folding edge to the sheet. The purpose of such construction is to prevent buckling the sheet when the fold is sealed, and to prevent breaking the sheet at a false folding line. Although the forming members act as an interior support, and the sheet is folded over them, their thickness is somewhat immaterial, my sealing and discharging devices acting to flatten even a roll-like fold. I prefer to construct them symmetrically thinned down toward their free end, as indicated at 40 and 40^r, in order to extend them to a point 30 near the leading edge of the sheet to be folded, or even beyond it, the purpose of the construction being to reduce the danger of buckling by extending the interior support, the leading edge commonly being a folded edge that cannot be 35 trusted to break properly without such support. I prefer to construct them narrowed or cut away, as at 41 and 41^r, Fig. 1a, for purposes explained later.

The present invention makes use of reciprocating devices for laying the sheet over said forming members in a fold. Those in the embodiment shown in Figs. 1 and 2 are movable laterally, along with their supporting structure. As employed in said embodiment they are described as follows: Sub-frames 27 and 27^r have journaled upon them respectively in suitable planes the short shafts 42 and 42^r, each of which bears attached near either end the arms 43 and 43^r respectively. These arms have journaled in them 50 respectively shafts 44 and 44^r, attached upon which are the short arms 45 and 45^r, to form a hinged construction. Arms 45 and 45^r have journaled in them axles 46 and 46^r of rollers 47 and 47^r. Tracks 48 and 48^r, attached upon sub-frames 27 and 27^r respectively, support said rollers near their ends, said tracks acting as guides to control the course of said rollers and also acting frictionally to rotate them, springs 49 serving to press said rollers upon said tracks, through pins 50 and 51 on arms 43 and 45 and arms 43^r and 45^r respectively. Axles 46 and 46^r have attached upon them, preferably as tangential extensions of the peripheries of said rollers, blades 52 and 52^r. It will be understood that the diameter of said rollers will preferably be such that the rotating of them upon their tracks will bring such blades from the position shown in Figs. 1 and 2 into a position flat upon forming members 39 and 39^r, or upon the sheet folded thereover, 70 shortly before the end of the work-stroke of said rollers, so that the latter part of their action will be a sliding or smoothing action. It will be understood also that in this construction the folding function is divided between said rollers 75.

and said blades, each possessing certain advantages, and that in some uses the rollers may be employed without the blades, and that in some uses the blades may be employed without the rollers, or using only such portions of the rollers as bear upon the tracks, or using another arrangement of wheel-and-track control, as for example such as is shown in Fig. 3, the precise controlling devices, or type thereof, being immaterial.

10 In the said embodiment of the invention shown in Figs. 1 and 2 the actuating devices for said reciprocating devices are described as follows: Shafts 42 and 42^r previously described have attached respectively thereon arms 53 (Fig. 1), to the free ends of which springs 54 are connected, the other ends of said springs being attached upon sub-frames 27 and 27^r respectively in such manner as to act pullingly upon said arms. Said shafts 42 and 42^r also have attached upon them 20 respectively short arms 55 and 55^r which terminate in radially extending axles 56 and 56^r for cam rollers 57 and 57^r. Said cam rollers bear upon the working surface of cams 58 and 58^r, which are mounted slidably upon shaft 14 previously described, and are rotated by it conveniently through laterally extending pins 59 and 59^r attached upon said cams, said pins having a sliding engagement with arms 60 and 60^r attached on said shaft, namely through holes in the said arms. Said cams have their lateral position controlled by sub-frames 27 and 27^r through grooved hubs 61 and 61^r, the grooves of which are engaged by fingers 62 and 62^r attached upon said sub-frames, studs 63 and 63^r serving to position 30 said yokes laterally. Actuating cams 58 and 58^r referred to have a working contour suitable for giving the desired movement to the connected parts. The arrangement is such that rollers 41 and 41^r, and blades 52 and 52^r, are directed against the sheet in a reciprocating action effective to fold it over forming members 39 and 39^r whatever the lateral position may be of the working parts.

The sheet-positioning devices employed in said embodiment are described as follows: Sub-frames 27 and 27^r have attached upon them frame extensions 64 and 64^r, bearing journaled therein shafts 65 and 65^r. Attached upon said shafts to rock with them are the longitudinally extending paper clamps 66 and 66^r, one of the functions of which is to serve as paper guides, and another, to serve as paper supports. The further functions thereof will be described later. One of the functions likewise of forming members 39 and 39^r, as employed in this embodiment, is to serve as paper guides, and another, to serve as paper supports. The sheet to be folded is advanced by the sheet-advancing means previously described into the control of said guiding and supporting devices, and upon leaving said means falls by the force of gravity, or the force of its inertia, or both, until arrested or stopped by stops 67 and 67^r, attached upon sub-frames 27 and 27^r. The sheet is indicated at 68. Said stops are positioned laterally by outstanding studs or projections on said sub-frames. It will be understood that any rebounding from such stops may be controlled as in common practice by any approved means. In most uses the rebounding sheet in this construction will settle back securely against the stops by the force of gravity without further control. It will be understood also that the sheet is supported on both sides in this construction because of its nearly vertical position when brought to rest. The invention is not limited to the means

described for bringing the sheet to rest in folding position, nor to the type of means described.

The means employed in the said embodiment for clamping the sheet against displacement are described as follows: Longitudinally extending clamps 66 and 66^r before described, attached to rock with shafts 65 and 65^r respectively, have attached upon the under side thereof the down-standing elbowed operating levers 69 and 69^r, which project engagingly under the laterally extending rail 70, carried on arms 71, so as to be engaged by it whatever the lateral position of the levers. Also attached upon the under side of said clamps are springs 72 and 72^r, arranged to bear against sub-frames 27 and 27^r in such manner as to rock said clamps closely upon forming members 39 and 39^r, and therefore upon the sheet. Rail 70 is rocked downwardly upon levers 69 and 69^r aforesaid by spring 73, which is strong enough to overcome the force exerted by springs 72 and 72^r, through the following structure: Arms 74 are attached upon rocking shaft 14, journaled at either end in side frames 6. Said shaft bears also attached upon it an operating arm 75 having a pin 76 thereon which is journaled in one end of connecting rod 77. The other end of said connecting rod is journaled upon a pin 78 on one of the swinging arms 79 and 79^r. Said latter arms are journaled upon drive shaft 7 for an axis upon which to be rocked, and they are connected into an operative unit by struts or stays 80. Arm 79 is extended at the lower end in elbows or branches, one of which bears attached thereon pin 81 on which cam roller 82 is journaled in such manner as to be engaged by cam 83, attached upon shaft 14 before mentioned. Another of the branches of arm 79 bears on it a pin 84, upon which one end of connecting rod 85 is journaled, the other end thereof being journaled upon a pin 86 on elbow lever 87. Said elbow lever or arm is attached upon shaft 88, journaled in side frames 6 at either end, and it bears also a pin 89, upon which one end of spring 73 before mentioned is attached, the other being attached upon side frame 6. The arrangement is such that cam 83 acts against the pressure of spring 73 to raise rail 70 from engagement with elbowed levers 69 and 69^r, whereupon springs 72 and 72^r close clamps 66 and 66^r against forming members 39 and 39^r, and therefore upon the sheet. Spring 73 in turn acts to lower rail 70 into engagement with elbowed levers 69 and 69^r, thereby rocking said clamps into open position against the force of said springs 72 and 72^r, when cam 83 permits this action. It will be noted that in Figs. 1 and 2 for the sake of clearer illustration clamps 66 and 66^r are shown in open position, although rail 70 has been raised by the parts described from depressing the levers 69 and 69^r. It will be noted also that in Fig. 2 the sheet shown in Fig. 1 is removed, also for the sake of clearer illustration. It will be understood furthermore that although said clamps engage upon the sheet on a line adjacent to the folding line, their transverse position is somewhat immaterial, and that although they are arranged longitudinally as respects the folding line, the invention is not limited to this arrangement, and that although they are shown as bearing against the forming members, such construction is not necessarily employed in all cases. It will be noted also that in some uses a clamping means will not be required.

The embodiment described makes use of the following devices for removing or discharging the folded sheet, or for advancing it to another

folding stage, and for pressing down or sealing the folds produced thereby: Arms 79 and 79^r referred to as journaled on shaft 7 so as to be rocked thereon have journaled in them shafts 90 and 91, the latter in bearings slightly elongated, so as to permit said shafts to be slightly separable, namely against the spring pressure drawing them together. Said shafts are rotated from drive shaft 7 through sprocket wheel 92 attached thereon, sprocket wheel 93 attached on shaft 90, chain 94 connecting the sprocket wheels, toothed wheel 95 also attached on shaft 90, and toothed wheel 96 attached on shaft 91, said toothed wheels meshing. The relation of the several wheels is such that the shafts are rotated an even number of times for each revolution of toothed wheel 13, so that the gated rolls thereon may cooperate in a timed action with the parts actuated by said wheel. Two of these rolls, indicated at 97 and 97^r, are keyed slidingly on shaft 90 through keys 98, and two of them similarly indicated are keyed slidingly on shaft 91 through similar keys. Said rolls are constructed with unbroken bearer portions 99, and are supplied with recesses or gateways 100 and 100^r to admit the folded-over leading edge of the sheet without unsettling the fold, but in some uses neither will be required, nor will a timed rotation thereof in all cases be needed, nor a toothed drive therefor. They are supplied also with circumferentially-extending shallow recesses 101 and 101^r, to provide clearance for the thinned down ends 40—40^r of forming members 39—39^r, and to soften the sealing of the fold. In some uses these will not be required. The remaining portions 102 and 102^r of the rolls are of full diameter; being spring-pressed together, when presented to the sheet they engage it frictionally, namely through cut-away spaces 41 and 41^r in said forming members. It will be noted that neither the wheels or rolls for the purpose, nor forming members to cooperate therewith, namely having cut-away spaces therein behind unbroken forming edges, are limited to this construction, nor to a construction in which only the one edge of a forming member is unbroken, nor to a construction useful only with sheet-discharging devices. In the embodiment described the spring pressure for pressing the rolls together is applied through yokes 103 and 103^r on shaft 91. Springs 104 connected to said yokes are attached at the other end to arms 79—79^r. The rolls are positioned laterally through grooved hubs 105 and 105^r thereon, the grooves being engaged by finger extensions 106 of stop members 67 and 67^r previously described, attached upon the laterally movable sub-frames 27—27^r, thus causing the rolls to be shifted on their shafts by said sub-frames and maintaining them in operative relationship therewith. The invention is not limited to any special means for accomplishing the purpose. It is not limited to the use of any special sealing or discharging means, nor is any sealing means in all cases required. In the embodiment described, the folded sheets are stacked by means of a fly 107, attached upon rock-shaft 88, but any usual or approved means may be employed, and in some uses no stacking means will be required.

Means are employed in the present embodiment for holding the sheet in position after folding, before it has passed securely into the control of the further devices. These are described as follows: Sub-frames 27 and 27^r have attached thereon (Fig. 2) the bent-down edges of paper tables 108 and 108^r, opened suitably to permit the

passage of rollers 47 and 47^r and blades 52 and 52^r. Said paper tables have the additional support of up-standing pieces 109 and 109^r, supported slidingly upon the transversely extending rod or beam 26. They serve to support the wider portions of the sheet prior to folding. Attached upon piece 109^r, and upon paper table 108^r, is a cam-like track 110, so positioned as to engage a cam roller 111 journaled on pin 112 on extension 113 of the nearer of arms 45^r. The construction is shown in Fig. 2. Track 110 in function is an extension of tracks 48^r; it lies in the path of said cam roller, and its working contour is such that arms 45^r are raised slightly thereby at the end of their stroke, thus easing the pressure of roller 47^r and blade 52^r upon the sheet sufficiently to enable the sheet to be withdrawn longitudinally from beneath them, in advance of the retraction of said roller and blade. It will be noted that the gated rolls described act controllingly upon the fold at the leading edge thereof, and in some uses the present construction will not be required. Its function is to control the natural spring of the fold throughout its length, prior to its engagement thereby. The invention is not limited to any particular construction for the purpose, even when the function is performed.

The means employed in this embodiment of the invention for indicating in advance, that is to say before the sheet is entered, and at the feed-board, where such indication is usually most useful, where the later folds will fall, are described as follows: In the mechanism shown in the drawings the longitudinal folding lines are the ones whose positions are indicated. Since such folding lines in this case are established through the forming members, and the forming members are attached upon blocks 33 and 33^r, positioned adjacent to the feed-board, I attach upon them pointers 114 and 114^r respectively to act as indicators indicating where such lines will fall with respect to the feed-board, or with respect to pressure roll 3, both of which have a fixed lateral datum position. As arranged, the feed-board edge lies rearwardly of the pointer, and the pressure roll forwardly of it. The operator, knowing where he wishes his sheet to be folded, can lay it upon the feed-board exactly in the desired position before setting his side-guides; or he can place the sheet against his side-guides and then bring the folding mechanism into the exact desired position. In folding machines in commercial use at present the operator has no such assistance. The invention is not limited to any precise form of indicator employed for the purpose, nor to the precise later folding lines indicated, nor to the precise position of the indicator. In some uses an indicator for this purpose will not be required.

The mechanism described is operated as follows: The operator in practice frequently folds a sheet by hand for guidance. This he may lay upon the feed-board. Through handle 37 or 37^r he now turns shafts 32—32^r, shafts 28—28^r through their chain and sprocket connections are rotated in unison therewith, and forming members 39 and 39^r are approached or separated to the required extent, indicators 114 and 114^r guiding him accurately, without requiring the exercise of skill. If for any reason an operator wishes to adjust the position of each longitudinal fold separately, as for example to avoid making feeder adjustments or to avoid changing his side guides, he is enabled to do this by first withdrawing pins 30 so as to disconnect the right-hand and left-

hand threaded shafts, each group being independently operable. It will be understood that said pins will usually be withdrawn or retained for a given user in advance, to meet habitual needs or preferences, and will not ordinarily be changed back and forth, however easily the change may be made. In some uses said pins need not be withdrawn; in such cases one set of chain-and-sprocket connections may be dispensed with. In some uses all adjustments can be made using shafts 28 and 32 alone, or shafts 28^r and 32^r alone. If only one size of sheet is to be folded, all adjustment devices may be dispensed with, without affecting the remaining features of the invention.

The operator completes making his adjustments and positions a sheet to be entered, knife 1 strikes it between pressure rolls 2 and 3, and the transverse fold is made. The sheet is now advanced by said rolls into the open channel between forming members 39-39^r and clamps 66-66^r. Upon passing from between the rolls it is carried by gravity along said channel until arrested by stops 67 and 67^r in folding position. It will be understood that cam 83 meanwhile has retracted rolls 97-97^r slightly, so as not to engage them with the sheet-edge, but not to an extent to cause clamps 66-66^r to close.

The sheet has now been folded transversely, advanced from this folding stage, and positioned for further folding. Cam 83 now retracts rolls 97-97^r further, into the position shown in Fig. 1, thereby permitting springs 72-72^r to rock clamps 66-66^r against the sheet. As was previously explained, in Figs. 1 and 2 said clamps are shown in opened position, in order to show the construction thereof more clearly, but in this operating position said springs would have closed them. The retracted position of rolls 97-97^r as shown in Fig. 1 also removes said rolls from all interference with the sheet during its folding movement. The means employed for the purpose are somewhat immaterial; I prefer to employ cam 83 through the parts described.

The reciprocating devices for folding the sheet over the forming members are now brought into action. In the embodiment described the left-hand fold is first laid over, cam 58 on shaft 14 operating to move roller 47 upwardly along tracks 48 upon which it is spring-pressed, thus bringing it into broadside engagement with the sheet and lifting the sheet. The rotating of roller 47 eventually brings blade 52 likewise into engagement with the sheet. Roller 47 is rolled thus along tracks 48 until it arrives at the edge of forming member 39, when it passes from said tracks to roll broadside across said forming member, with the sheet underneath, folded over the forming member. The sheet may or may not be broken at the folding line by this action, and the fold produced therein may or may not be sharply pronounced. The rolling action of the roller in some uses folds the sheet more firmly about the forming member than would a blade action alone. The blade likewise in some uses has advantages over a roller used alone. Either may be employed without the other in some uses. The action of the two employed together results in the laying of the blade flatwise upon the sheet shortly before the end of the work-stroke, and during the remainder of the stroke it slides flatwise upon the sheet. Retraction is effected by spring 54, cam 58 controlling the action thereof. It will be noted that at the end of the retracting stroke blade 52 is eased against tracks 48, which auto-

matically position it for the work-stroke which follows. The invention is not limited to the use of a blade in laying down a fold in combination with a roller, nor to the use of either blade or roller as a folding agent.

In the present embodiment the contour of cam 58 is such that roller 47 does not leave forming member 39 when retracted until the opposing right-hand roller 47^r has passed upon forming member 39^r, so that the fold laid down by said roller 47 and blade 52 is securely held down by one or other of said rollers, until the folded sheet passes into further control. Upon the approach of roller 47^r however, roller 47 is completely retracted, roller 47^r and blade 52^r now holding down both the earlier fold and the overlying fold made by them. It will be noted that in some cases blade 52 can be made to act as a supplementary forming member over which the sheet may be folded, if cam 58 be given a suitable working contour to delay said blade at the end of its work-stroke until roller 47^r and blade 52^r fold the sheet thereover. In such cases retraction will preferably be made shortly after said roller 47^r passes over the edge thereof and it may or may not be accompanied by the easement described in connection with said roller. The resulting fold will be a Z or accordion fold, if 3-ply, or if the sheet is wide enough, and suitably positioned, a 4-ply fold. Such latter fold will or may be made along three folding lines, if the said blade 52 does not extend to the edge of forming member 39^r, the fold formed over it lying within the other two.

The folding action of roller 47^r and blade 52^r has its source in cam 58^r, and it is similar to that of roller 47 and blade 52 described. The action is timed to begin as said roller 47 and blade 52 pass from their work-stroke to their retracted stroke. Immediately before the end of their folding action roller 47^r and blade 52^r are eased slightly from the sheet, a cam roller 111 connected thereto engaging with cam segment 110, thereby raising the same, as has been explained. Cam 58^r is so shaped as to hold said roller 47^r and blade 52^r in this position at the end of their work-stroke until the sheet has been withdrawn from beneath them. The action results in restraining the folded-over sheet from springing out of place before passing into the control of the sealing and discharging devices. Retraction is made by right-hand spring 54.

As has been explained, immediately after the positioning of the sheet, cam 83, acting against the pressure of spring 73, swings gated rolls 97-97^r into their retracted position, namely that shown in Fig. 1, partly to remove them from the folding path, and partly through this movement to permit clamps 66-66^r to be closed upon the sheet prior to its folding. As has also been explained, the sheet is then folded over the forming members by the reciprocating devices. This action lifts the sheet away from stops 67, which now lie outside the paper path. A further revolving of cam 83 now permits spring 73 to swing gated rolls 97-97^r forwardly toward the folded leading edge of the sheet, and at the same time to open clamps 66-66^r against the inferior pressure of springs 72-72^r. The timing arrangement is such that when this action begins the rolls have been rotated until their gated recesses face the sheet, as in Fig. 1. They arrive at their forward working position with the folded-over leading edge of the sheet entered into these recesses. The further revolving of the rolls brings the fur-

ther edges of the recesses together closely upon the fold, in this case equally from either side, whereupon the further rotation still of them draws the sheet between them in a sealing and discharging action. It will be understood that the rolls are rotated from drive shaft 7, which turns in counter-clockwise direction, giving them effective rotation for the purpose. It will be understood also that the thinned-down ends 40-40^r of the forming members 39-39^r likewise extend between the rolls, but are not engaged because of the recesses 101-101^r over which they lie. They serve as an interior support at the leading edge of the sheet being folded. The fold produced by the rolls will be harder or softer according as recesses 101-101^r are shallower or deeper. In some uses this construction will not be required. The more positive engagement with the sheet is had through the full diameterd portions of the rolls indicated at 102 and 102^r, which meet through the cut-away spaces indicated at 41 and 41^r in the forming members, the lateral edges of the gated recesses acting like grippers presented to the fold and closed. The mechanism in some aspects may be regarded as a special form of gripper mechanism intermittently presented to the sheet, or as gripping rolls likewise intermittently engaging it. It employs a reciprocating actuation combined with a closing actuation, to which has been added a revolving feature effective to remove the sheet and seal the fold. The invention is not limited to any particular means for performing any of these functions.

35 The embodiment described shows also a stacking mechanism, namely in fly 107, but the invention does not reside therein, such mechanism being in common use. Any approved stacking means may be employed, or none at all.

40 The embodiment of the invention shown in Fig. 3 does not require the use of separable reciprocating devices for folding the sheet over the forming members, and the same are shown mounted in a laterally fixed position. Instead of employing both a roller and a blade in the folding operation, it employs a blade alone, without limiting itself thereto or to any particular form or type of device for the purpose. Instead of employing clamping devices longitudinally disposed toward the forming members, it makes use of clamps engaging with them crosswise, and having a different control. Instead of employing separable gated rolls, it makes use of rolls in a fixed lateral position. The mechanism as a whole is simpler, and is intended to serve simpler uses. It is described as follows:

60 The sheet is positioned for entering as before, with the assistance of the indicating means described, namely pointers 114 and 114^r attached upon separable blocks 33 and 33^r, supported as described. It is given a transverse fold, when such is required, by the knife-and-rolls devices described, and is advanced as described by rolls 2 and 3 into a channel defined on the upper side by forming members 39³ and 39^{r3} attached upon said blocks. The said forming members used in this embodiment have rounded edges over which the sheet is folded, instead of angular, but otherwise they are similar in every way to forming members 39 and 39^r before described. The lower wall of said channel, however, makes use of structure departing from that described; instead of employing a clamping device for a paper support it employs paper table 108³, attached upon a fixed cross-frame 27³ on frame 6. Stops

65

67³ and 67^{r3} are similar to stops 61 and 67^r, except that they are attached upon said fixed cross-frame instead of upon movable subframes 27 and 27^r.

The reciprocating devices employed in this embodiment for folding-over the positioned sheet are described as follows: Cams 58³ and 58^{r3} for actuating the same in this case are fixedly attached upon shaft 14, instead of slidingly. Attached at either end upon side frames 6 are twin cross-farmes 27^{3a}, having journaled therein the ends of rock-shafts 42³ and 42^{r3}, upon which are attached arms 55³ and 55^{r3} terminating in radially extending axles 56³ and 56^{r3}, on which are journaled cam rollers 57³ and 57^{r3}. Said rock-shafts 42³ and 42^{r3} also have attached upon them toward either end reciprocating arms 43³ and 43^{r3}, each pair thereof joined by braces or struts 50³. Said arms bear journaled therein at their upper ends shafts 44³ and 44^{r3}, on which are attached blades 52³ and 52^{r3}. Said blades have attached thereon the downstanding elbow-arms 45³ and 45^{r3}, the lower ends of which bear pins 46³ and 46^{r3}, on which are journaled rollers 47³ and 47^{r3} for controlling the sheet-engaging action of the blades. Said rollers engage rollingly upon track-like cams 48³ and 48^{r3}, on cross-frame 27³ before mentioned, being pressed against the same by springs 49³ and 49^{r3} respectively, through pins 51³ and 51^{r3} on arms 45³ and 45^{r3}, and struts 50³ on arms 43³ and 43^{r3}. Said latter arms are retracted after their work-stroke by springs 54³ attached thereon, said springs being also attached upon side frame 6. The arrangement is such that cam rollers 57³ and 57^{r3} are actuated by cams 58³ and 58^{r3} against the pull of said springs. It will be noted that neither embodiment is limited to the use of blades with the structure described, the blade construction being merely a preferred construction, chosen for its lightness and simplicity.

The clamping devices employed in this embodiment comprise a laterally extending clamping member 66³ attached centrally on arm 66^{3a}, said arm being attached in turn upon shaft 65³, journaled at either end on cross-frame 27³. The 45 clamping member is constructed long enough to bear against forming members 39³ and 39^{r3} in every lateral position thereof. A downwardly-extending arm 69³ bears on it pin 81³ on which is journaled cam roller 82³ adapted to engage upon cam 83³ attached on shaft 14. A spring 72³ on said shaft 65³ is attached to rotate said shaft and thereby press clamping member 66³ against the sheet, cam 83³ acting to open the clamp, spring 72³ to close it. Said clamping member meets the sheet 55 at a point beyond the end of paper table 108³. Since said clamping member bears upon the sheet at two points, namely where supported by the right-hand and left-hand forming members, the sheet is held with sufficient firmness against displacement during the folding operation.

The discharging and sealing devices are as are shown in Figs. 1 and 2, except that instead of employing separable rolls the present embodiment makes use of longer single rolls 97³. These are 65 constructed having continuous bearing surfaces 99³ and 99^{r3} at their ends. Each is supplied with a laterally extending recess or gateway like those shown at 100 and 100^r, Fig. 1. Each is also supplied with right-hand and left-hand circumferential recesses, indicated at 101³ and 101^{r3}, sufficiently broad to admit the thinned-down ends 40 (Fig. 1) of the forming members in the several lateral positions thereof. Their functions are the same as those of circumferential recesses 101 and 75

101. The rolls are constructed of full diameter centrally, as indicated at 102³. Whatever the lateral position may be of the forming members, this central portion of the rolls will close grip-
5 pingly upon the folded sheet and pull it forward in a sealing and discharging action. It will be under-
stood that said rolls are fixedly attached upon
shafts 90 and 91, Figs. 1 and 2, which are driven
as in the other embodiment.

10 102. The mechanism is operated as follows: Adjust-
ments are made in advance at the feed-board, as
before, the sheet is given the transverse fold, if
such is required, and rolls 2 and 3 advance it
15 into the control of the positioning devices. As
before, it is arrested in folding position by stops,
and then held by clamping devices against dis-
placement. Cam 58³ through arms 55³ now moves
blade 52³ toward the right, whereupon roller 47³
20 lifts it against the sheet and bends the sheet up-
ward. In the action that follows the blade car-
ries the sheet across forming member 39³ in a fold.
Cam 58³ holds the blade here in arrested position
25 until the right-hand fold is made in similar man-
ner by blade 52³ under the actuation of cam 58³,
blade 52³ being likewise held in arrested position
at the end of its work-stroke. The said blades
30 are very thin, and moreover press upon the sheet
in a manner not bind it, so that in many uses
the sheet is removable without easing their pres-
sure, but the track-like cams 48³ and 48³ may be
35 so shaped as to raise them slightly. It will be
noted that in such use the second fold is made
not only over forming member 39³, but over blade
52³ as well. The sheet may therefore be so posi-
40 tioned as to receive a three-ply Z or accordion
fold, blade 52³ in such case acting as a supple-
mentary forming member, and that if the sheet
is wide enough it may receive a four-ply nested
45 fold on three folding lines.

46. The sealing and discharging devices operate to
remove the sheet and press down the fold as has
been described in the case of the previously de-
scribed embodiment, the gated rolls closing upon
the fold in the same manner and sealing the fold
50 in the same manner.

51. It will be understood that although in both em-
bodyments the left-hand folding devices are de-
scribed as acting first, they may just as well act
last and the right-hand devices first, according
55 as the controlling cams are shaped to time them.

56. Certain of the features shown herein are
claimed more broadly in my pending application
for patent filed July 10, 1929, Serial No. 377,255.
The embodiments shown herein make use of a
57 forming member or members over which a sheet
may be folded, and timed devices acting inter-
mittently to fold the sheet thereover. The em-
bodyments shown in said pending application also
make use of such features. In the embodiments
60 shown herein said forming members are con-
structed finger-like or tongue-like. In the said
pending application forming members of similar
construction are shown. The embodiments
shown herein make use of threaded shafts to
65 facilitate adjusting the position of the longitudi-
nal folds. The embodiments shown in said pend-
ing application also make use of threaded shafts
for the purpose. In the devices shown herein
gated devices are employed for closing a longi-
70 tudinal fold, and also for discharging the folded
sheet. In the said pending application gated de-
vices are employed for similar purposes.

71. Certain of the features shown herein are also
claimed more broadly in my pending application
for patent filed October 11, 1930, Serial No.

488,087, now become U. S. Patent No. 1,838,106.
In addition to forming members such as have
been referred to, and devices acting intermit-
tently to fold the sheet thereover in a timed ac-
tion, the embodiments shown herein make use of
sheet-positioning means for bringing the sheet
5 into folding position prior to the folding action,
said folding devices operating while the sheet is
stationary. The embodiments shown in said
pending application also make use of such sheet-
positioning means. The embodiments shown
herein make use of gated rolls for closing or seal-
ing the fold, and for discharging the folded sheet.
The embodiments shown in said pending applica-
tion also make use of gated rolls for these pur-
10 poses.

15 It will be noted that in the embodiments of the
invention shown in my pending application Serial
No. 377,255 before mentioned, the sheet is ad-
vanced, folded and discharged while in continu-
ous forward motion. In the embodiments shown
20 in my pending application Serial No. 488,087, now
U. S. Patent No. 1,838,106, also previously men-
tioned, the sheet is advanced, stopped in folding
position, thereafter folded, and the folded sheet
25 presented to devices that discharge it. In the
embodiments shown in the present application,
the sheet is advanced, stopped in folding pos-
ition, thereafter folded, and the folded sheet dis-
charged by devices presented to it. It will be
30 noted further that the timed devices operating
intermittently to fold the sheet over the forming
members are shown more specifically in my said
pending earlier application Serial No. 377,255 as
35 revolving devices. Said timed folding devices as
shown in my pending application Serial No.
488,087, now U. S. Patent No. 1,838,106, before
mentioned are also more specifically revolving de-
vices. The timed devices operating thus inter-
mittently as shown in the present application are
40 more specifically reciprocating devices. It will
be noted also that the devices shown in my pend-
ing application Serial No. 377,255 referred to, to
facilitate adjusting the position of the longitudi-
45 nal folds, more specifically employ threaded
shafts to control the lateral position of the timed
folding devices. The embodiments shown in my
present application more specifically make use
50 of such shafts, but in addition means are shown
therein extending such use to the separable form-
ing members, thereby simplifying the construc-
tion and economizing the lateral space required
55 by the connecting devices.

Having thus clearly explained the nature and
objects of my invention and the manner of apply-
56 ing the same, I claim as new and desire to secure
by Letters Patent.—

1. In a folding machine, in combination: a
forming member over which a paper sheet may
be bent to form a fold therein; a member movable
60 against the sheet to fold it thereover; means for
introducing the sheet to be folded into the control
thereof; and reciprocating devices adapted to ad-
vance and retract said movable member in a fold-
65 ing action.

2. In a folding machine, in combination: a
forming member; a member adapted to fold a
paper sheet thereover; means for introducing the
sheet to be folded into the control thereof; track
70 devices connected to one of said members to di-
rect the folding action of the same; and means
giving said track-directed member a timed action
effective to cause the sheet to be folded thereby.

3. In a folding machine, in combination: a
forming member; devices adapted to fold a paper

- sheet thereover; means for introducing the sheet to be folded into the control thereof; means giving said folding devices a reciprocating movement against and away from the sheet; and track devices connected to direct said movement.
4. In a folding machine, in combination: a forming member adapted to support a paper sheet at the folding line; a roller adapted to fold a sheet thereover, said roller axled longitudinally thereto; means for introducing the sheet to be folded into the control thereof; and operating means connected to actuate said roller against the sheet at said forming member so as to fold the same thereover.
- 10 5. In a folding machine, in combination: a forming member; a roller having an axis longitudinal thereto; sheet-positioning means; reciprocating devices adapted to give said roller an action against the sheet effective to fold the same over said forming member; and track means connected to direct the folding action of said roller.
- 15 6. In a folding machine, in combination: a forming member; reciprocating arms axled longitudinally thereto; a roller journaled therein; track devices adapted to support the same; springs pressing said roller thereon; sheet-positioning means; and means connected to said arms effective to operate said roller against a positioned sheet at said forming member in a folding action.
- 20 7. In a folding machine, in combination: a forming member over which a paper sheet may be folded; a blade member adapted to bend a sheet thereover; means for introducing the sheet to be folded into the control of said members; and devices adapted to give one of said members a movement against the sheet effective to cause the folding thereof.
- 25 8. In a folding machine, in combination: a blade movable against a paper sheet in a folding action; a forming member adapted to cooperate therewith from within the fold in folding paper; sheet-positioning means; and means adapted to give said blade a reciprocating movement timed to fold the positioned sheet over said forming member.
- 30 9. In a folding machine, in combination: a forming member over which a paper sheet may be folded, and having one end free for the longitudinal discharge of a sheet folded thereover; a blade adapted to fold a sheet over said member; means for introducing the sheet to be folded into the control thereof; reciprocating devices adapted to operate said blade against the sheet in an action effective to fold the same; and means adapted to effect the longitudinal discharge of the folded sheet from said forming member.
- 35 10. In a folding machine, in combination: a forming member over which a paper sheet may be folded; reciprocating arms axled longitudinally thereto; a blade connected to said arms; means adapted to introduce the sheet to be folded into the control of said blade; and means adapted to cause said arms to bring said blade into an engaging action against the sheet effective to fold it over said forming member.
- 40 11. In a folding machine, in combination: a forming member over which a paper sheet may be folded; a blade movable against a sheet to fold it thereover; means for introducing the sheet to be folded into the control thereof; reciprocating devices connected to operate said blade; and track devices connected to direct the folding movement of the blade against the sheet.
- 45 12. In a folding machine, in combination: a forming member over which a paper sheet may be folded; a roller axled longitudinally thereto, said roller having a blade extension thereon; means for introducing the sheet to be folded into the control thereof; reciprocating devices connected to bring said roller and its blade into an engaging action against the sheet effective to fold the same over said forming member; and track means adapted to direct the folding action of said roller and blade.
- 50 13. In a folding machine, in combination: forming devices over which a paper sheet may be folded, said devices having one end free for the longitudinal discharge of a sheet folded thereover; devices adapted to fold a sheet over said forming devices; means adapted to introduce the sheet to be folded into the control thereof; a cam connected to give one of said several devices a reciprocating movement effective to cause the folding of the sheet; and means adapted to effect the longitudinal discharge of the folded sheet from said forming member.
- 55 14. In a folding machine, in combination: a forming member over which a paper sheet may be folded; a folding member adapted to fold the sheet thereover; reciprocating devices connected to the folding member to operate the same; and means adapted to control the tendency of the sheet to unfold after its folding by the folding member over the forming member.
- 60 15. In a folding machine, in combination: a forming member over which a sheet may be folded and from which it may be longitudinally discharged; folding devices adapted to fold the sheet thereover; means connected to said devices to operate the same; and means connected to the folding devices to support and detain them above the folded sheet, for the purpose of controlling its tendency to unfold after folding.
- 65 16. In a folding machine, in combination: a forming member; a roller adapted to fold a sheet thereover under spring pressure; means for positioning the sheet to be folded; means connected to operate said roller; and means adapted to ease the pressure of said roller upon the folded sheet, said means including a track and track rider, for the purpose of permitting the discharge of the sheet before passing from the control of said roller.
- 70 17. In a folding machine, in combination: a laterally movable forming means over which a sheet may be bent; means for introducing the sheet to be folded into the control thereof; a threaded shaft adapted to vary the lateral position of said forming means; a handle connected to said shaft for the manual operation of the same; and means effective to bend a sheet over said forming means in the several lateral positions thereof.
- 75 18. In a folding machine, in combination: a laterally movable forming means over which a sheet may be bent; means for introducing the sheet to be folded into the control thereof; parallel rails adapted to support said forming means slidably in the operative plane thereof; a threaded shaft adapted to vary the lateral position of said forming means on said rails; and means effective to bend a sheet over said forming means in the several lateral positions thereof.
- 80 19. In a folding machine, in combination: separable forming devices; separable devices cooperating therewith effective to bend a sheet thereover; means for introducing the sheet to be folded into the control thereof; threaded shafts adapted to vary the separation of said forming and cooperating devices; and means adapted to

synchronize the rotation of said shafts, thereby coordinating the separation of said separable devices.

20. In a folding machine, in combination: separable forming devices; separable devices co-operating therewith effective to bend a sheet thereover; means for introducing the sheet to be folded into the control thereof; threaded shafts adapted to vary the separation of said forming and cooperating devices; sprocket wheels attached thereon; and a chain connecting the sprocket wheels to synchronize their rotation, thereby coordinating the respective positions of said forming devices relatively to said cooperating devices.

21. In a folding machine, in combination: folding devices adapted to produce a longitudinal fold in a sheet; means adapted to flatten said fold, said means including transversely axled 10 rolls adapted to admit the sheet-edge between them; and means adapted to give the rolls a reciprocating movement toward and away from sheet-engaging position.

22. In a folding machine, in combination: folding devices, including a forming member over which a sheet may be folded; and reciprocating devices adapted to discharge the folded sheet from said forming member, said devices supplied with an opening to admit the sheet-edge and adapted to engage the sheet between them in an action effective to remove it.

23. In a folding machine, in combination: folding devices, including a forming member over which a sheet may be folded; and cooperating gated rolls for removing the folded sheet from said forming member, said rolls movable toward said member and away from it for sheet-entering purposes.

24. In a folding machine, in combination: means for laying over or folding a sheet; a forming member adapted to cooperate in a folding action therewith from within the fold; and revolvable devices for moving the sheet longitudinally thereto, including a sheet-engaging roll recessed circumferentially to a depth sufficient to provide clearance for the forming member.

25. In a folding machine, in combination: a forming member over which a sheet may be bent; devices for folding a sheet thereover; means for introducing the sheet to be folded into the control thereof; and devices for flattening the fold produced thereby, including sheet-engaging pressure rolls circumferentially recessed adjacent to the free end of said forming member to provide clearance therefor.

26. In a folding machine, in combination: a folding mechanism adapted to produce adjustably positioned folds in material such as paper; a movable indicator; and means coordinating the indicating position thereof with the adjusted position of said folding mechanism when set to produce a given fold, thereby facilitating the adjusting of the same.

27. In a folding machine, in combination: a folding mechanism adapted to produce adjustably separable parallel folds in paper or the like; indicating devices; and means coordinating the indicating positions thereof with the adjusted positions of said folding mechanism when set to produce said folds.

28. In a folding machine, in combination: a folding mechanism adapted to produce an ad-

justably positioned longitudinal fold in a sheet; a movable indicator; and means coordinating the indicating position thereof with the adjusted position of said folding mechanism when set to produce a given longitudinal fold.

29. In a folding machine, in combination: a folding mechanism adapted to produce adjustably separable longitudinal folds in a sheet; separable indicators; and means coordinating the separation thereof with the adjusted positions of said folding mechanism when set to produce folds of a desired separation.

30. In a folding machine, in combination: a folding mechanism adapted to produce adjustably positioned folds in a sheet, said mechanism including a feed-board for supporting the sheet to be entered; a movable indicator adapted to co-operate in positioning a sheet thereon; and means coordinating the position of the indicator with respect to the feed-board with the adjusted position of said folding mechanism when set to produce a given fold.

31. In a folding machine, in combination: folding devices, including an adjustably movable forming member over which a sheet may be folded; a movable indicator; and means coordinating the indicating positions thereof with the several operative positions of said forming member.

32. In a folding machine, in combination: folding devices, including a support for the sheet to be entered and a laterally adjustable forming member over which an entered sheet may be folded; and a pointer connected to said forming member to indicate where a fold produced thereby will fall transversely to said sheet support, as an aid to the operator in making his adjustments.

33. In a folding machine, in combination: folding devices, including a forming member over which a paper sheet may be folded and devices operating intermittently against the sheet to fold it thereover; and clamping devices timed to hold the sheet against displacement during such folding action.

34. In a folding machine, in combination: folding devices, including a forming member over which a paper sheet may be folded and devices operating intermittently against the sheet to fold it thereover; clamping devices axled longitudinally to the fold produced thereby; and means connected to open and close the same.

35. In a folding machine, in combination: folding devices, including a forming member over which a paper sheet may be folded and devices operating intermittently against the sheet to fold it thereover; clamping devices for holding the sheet against displacement during the folding action; a spring closing the same upon the sheet; and means adapted to open said clamping devices to permit the positioning and discharging of the sheet.

36. In a folding machine, in combination: folding devices, including adjustably separable forming members and devices operating intermittently against the sheet to fold it thereover; spring-pressed clamping devices to hold the sheet against a folding displacement, said devices connected to operate in every adjustable position of said forming members; and means for opening the same for positioning and discharging the sheet, said means timed by cam action.
